(57) CLAIM

The ornamental design for a drywall mud hopper stand, as shown and described.

DESCRIPTION

FIG. 1 is a right side elevation view of the drywall mud hopper stand showing my new design, the left side elevation view being a mirror image, the broken lines showing the drywall mud hopper stand is for illustrative purposes only and forms no part of the claimed design;

FIG. 2 is a rear elevation view thereof;

FIG. 3 is a front elevation view thereof; and,

FIG. 4 is a top plan view thereof.
